(57) **CLAIM**

The ornamental design for a cockpit table for sailboat, as shown and described.

DESCRIPTION

FIG. 1 is a top and front perspective view of a cockpit table for sailboat showing my new design;

FIG. 2 is a top and front perspective view thereof; and,

FIG. 3 is a top plan view thereof.

The portions of the drawing shown in broken lines indicate surrounding structure, which forms no part of the claimed design.
